ANSWER

UNITED STATES PATENT OFFICE.

GEORGE H. EMERSON, ROBERT D. HAWKINS, AND FREDERICK T. KITCHEN, OF ST. PAUL, MINNESOTA, ASSIGNEES, BY MESNE ASSIGNMENTS, TO GOLD CAR HEATING & LIGHTING COMPANY, OF NEW YORK, N. Y., A CORPORATION OF NEW YORK.

ACETYLENE-GAS GENERATOR.

No. 927,780.

Specification of Letters Patent.

Patented July 13, 1909.

Application filed March 31, 1906. Serial No. 309,187.

To all whom it may concern:

Be it known that we, GEORGE H. EMERSON, ROBERT D. HAWKINS, and FREDERICK T. KITCHEN, citizens of the United States, and 5 residents of St. Paul, Ramsey county, Minnesota, have invented a new, useful, and Improved Acetylene-Gas Generator, of which the following is a full, clear, and exact description, such as will enable others skilled 10 in the art to which it appertains to make and use the same.

This invention relates to improvements in means for safely and economically generating acetylene gas from calcium carbide, and 15 has particular reference to improvements in acetylene gas generators for use upon railway cars.

The primary object of our invention is to provide an acetylene gas generator whereby 20 acetylene gas may be rapidly, safely and automatically generated in desired quantities and at desired times.

A further object of the invention is to provide a gas generator that shall be of simple and durable construction and so arranged 25 that it may be safely and quickly charged and emptied.

Another object of the invention is to provide a gas generator for and upon railway 30 cars and to so arrange and construct said generator that it may be charged and emptied from the exterior of the car, to the end that all danger of flooding the car with gas shall be avoided; and for the further purpose of lessening the cost of attendance upon 35 the generator.

Still another object of the invention is to construct and provide a gas generator for railway cars, which shall be small, compact 40 and of neat appearance; and a particular object is to provide a gas generator of great strength and so located within and combined with the framing of the car that it shall be practically impossible for the same to be 45 come a source of danger even though the car be wrecked.

A special object of the invention is to provide a gas generator which though of large capacity shall be of small size to the end 50 that it shall occupy little space in a car.

Still another object of the invention is to provide an acetylene gas generator of such form and construction that the feeding of the necessary carbide and water shall be ac-

complished without the use of moving parts 55 or other elements corresponding to the usual and complicated feeding mechanism now generally employed in acetylene gas generators.

A further special object of this invention 60 is to provide an acetylene gas generator of such construction that it shall be capable of automatically discharging the contained water and gas to the atmosphere in event of accident, as in case of its use upon a railway 65 coach and the coach is wrecked.

Still further objects of our invention will appear hereinafter.

Our invention consists primarily in an acetylene gas generator that has a tubular 70 body whose upper end projects through and above the roof of the car in position to receive a charge of carbide from that point, and whose lower end opens through the car floor so that the generator may be emptied without entering the car, all the known dangers 75 connected with the charging and emptying of acetylene gas generators being entirely avoided.

Further, our invention consists in a generator of the character above defined and which contains a deep carbide pocket or shell, the lower end of which is provided with a grating, in combination with means for maintaining a body of water in the lower part of 85 the generator body to receive the carbide which drops from said shell, the arrangement being such that the varying pressure of the generating gas causes the contained water to rise into contact with and drop away 90 from the carbide upon the grating, a high pressure of gas thus operating to stop or check generation and a lower pressure permitting the water to rise and partially submerge the carbide on the grating, thereby accelerating and checking the generation of 95 gas as required to maintain an approximately constant pressure in the generator and connected gas system.

Our invention also consists in various details of construction and in combinations of parts, all as hereinafter described and particularly pointed out in the claims.

The invention will be more readily understood by reference to the accompanying 105 drawings.

Figure 1, is a vertical, transverse section of a gas generator embodying our invention,

same being shown in position in a railway coach; Fig. 2, is a like sectional view of the lower end of the generator showing the discharge valve in open position; and Fig. 3, is 5 a detail view of the revoluble disk of the emptying valve.

Before proceeding with the description of our acetylene gas generator as applied to railway coaches, we deem it proper to state 10 that our apparatus is applicable to other uses, particularly to the furnishing of gas for the lighting of stores and residences. As such uses and also numerous modifications of the generator herein shown will 15 readily suggest themselves to one skilled in the art, we do not confine our invention to the specific construction, the arrangements or the use herein shown and described. Nevertheless, we consider our invention to be of 20 most importance and of greatest utility in connection with the lighting of railway coaches and trains, including locomotives; and desire to direct particular attention to its merits and advantages in that connection. 25 Referring now to the drawings, our generator, in its preferred form, is a long, tubular structure, placed at the side or in a corner of the car, with its ends protruding through the floor and the roof of the car. 30 Closures are provided for both ends of the structure at points outside of the car, these closures being of a kind adapted to facilitate access to the interior of the generator and to tightly close the ends thereof. The upper 35 part of the tubular body or structure is devoted to the reception of calcium carbide. The lower portion of the tubular body is made to contain the required body of water and serves as the residue or sludge chamber 40 to receive the slaked carbide. To these main elements of the generator are added the main reservoir and the gas tank, and the necessary gas pipes and conduits, which complete our 45 gas generator or system. The tubular structure preferably comprises a cylindrical tube or large pipe, 1, extending the full height of the car and projecting through the floor and the roof thereof. We prefer to employ a 50 seamless steel tube of heavy gage, as such a tube possesses sufficient strength to save it from breakage in event of a wreck.

Secured to the upper and lower ends of the tube, 1, are flanged castings 5 and 31. The bottom casting 31, rests upon the floor 55 timbers of the car. To it we secure the head, 32, containing a sludge discharge opening or duct 33. The head 32 is provided with lugs 32' and is secured to the casting 31, by swivel bolts, 34. A packing strip interposed between the casting and the head prevents leakage at the joint. On the upper face of the head 32, or preferably in a recess therein, is a valve disk, 37, for closing the discharge opening 33, in the head. 60 65 This disk contains an opening, 39, and when

the disk is turned, said opening may be made to register with the duct, 33, to discharge the sludge or residue from the generator. When the solid portion of the disk is turned over the opening 33, the lower end 70 of the conveyer is tightly closed to prevent the escape of the water normally confined therein. The head is an irregular casting and contains a barrel portion, 35, which forms a bearing for the valve stem, 36. 75 The valve is operated by means of the handle or lever, 38, on the stem, beneath the car. If desired the discharge opening or duct, 33, in the head 32, may be extended, by a pipe, 40, to any desired length. 80

The upper end of the generator body is closed by a cap or plate 7, which rests on the top of the casting or collar, 5, with suitable packing, 6, interposed. The plate is held in position by an arm 8, pivoted on a 85 lug, 10, of casting 5, and secured at the opposite side by a thumb nut or bolt, 11, extending from the lug, 12, on the part, 5.

If desired the carbide grating, 3, may be attached to the sides of the tube, but for 90 convenience we preferably make it a part of a separate carbide container, shell or cartridge. This shell comprises a tube 2, having a flange 4, at the top, whereby it is hung from the collar, 5. The shell 2, is 95 preferably tapered, being larger at the bottom than the top, our purpose in this regard being to insure the drop or feed of the contained carbide. In the lower end of the shell, 2, is the grating 3, formed of 100 curved bars and adapted to retain the lumps of carbide. As the upper end of the generator is above the roof of the car, it is always charged or filled from the exterior of the car, and thus all danger of flooding 105 the car with gas is avoided.

We arrange the water reservoir of our generator in the upper part of the car, the part here referred to is the reservoir, 15. The pipe, 14, leads from this reservoir, 15, to the lower part of the generator body, 1; opening into same a considerable distance beneath the grating, 3. A valve, 13, is provided in the water pipe. In practice this valve is either wholly closed or wide open; 110 no careful adjustment thereof being necessary, for reasons hereinafter stated.

23, is the filling pipe of the tank, 15. This opens through the roof of the car, in position to receive the end of a water pipe 115 or hose.

Upon the upper end of the pipe, 23, is a safety valve, which normally prevents the escape of gas through the water tank, but which permits the escape of gas when, if ever, the pressure of gas becomes excessive. The safety valve also operates to free the gas in the generator and tank in case the car 120 is overturned. The safety valve is of simple construction, comprising a casting 24, on the 125

pipe 23, and a small disk or valve proper, 25, provided with suitable gasket and held in place by the weighted lever, 27, the latter being pivoted on the casting, 24. The pressure at which the generator is to work is determined by the adjustment of the weight, 30, on the lever, 27. The valve lever may be lifted and the valve thrown open at any time for the purpose of filling the reservoir. As gravity is depended upon to hold the safety valve shut, it is obvious that the valve will swing open freely if the car is overturned.

The pipe, 23, projects into the reservoir, 15, to form an air trap in the upper part thereof. To permit the free flow of water from the reservoir, 15, to the generator proper, we use a small air pipe, 41, extending to a point below the floor of the car to the top of the reservoir. This pipe contains a check valve, 42, which will admit air to the reservoir, but which closes in the opposite direction to prevent the relief of either air, gas or water through the pipe, 41.

22, is an overflow or starting pipe connected with the generator 1, at a point close beneath the grating, 3. This pipe contains a valve 22', and is connected with the air pipe, 41, the lower end of the latter being enlarged as shown, that is the two pipes join 30 in a T from which the pipe, 41', extends through the floor.

The gas pipe, 17, extends from the upper part of the generator to a condenser, 18, and is thence continued in a pipe, 20, containing a valve, 21, and communicating with a gas reservoir, 13, beneath the car. The condenser, 18, is a metal tube, having a capped upper end, 19, which projects through the roof of the car. The gas pipe, 20, is connected to the intermediate portion of the tube, 18. The exposure of the end of the tube to the external atmosphere keeps the tube at a low temperature as required to condense the moisture carried over from the generator. 45 The condensation flows back to the generator through the gas pipe, 17.

The gas for use in the coach is taken from the reservoir, 13, and a reducing valve is usually employed in the burner pipe as shown, to insure a uniformity of pressure therein.

In operating our generator we prefer to use lump carbid which is coated or treated with oil, tar, wax or like substance, which 55 render the lumps partially moisture proof. Such coating while it prevents the decomposition and decrepitation of the carbid by water vapor, does not prevent decomposition when the carbid is submerged in water.

60 The operation of our generator is as follows: Assuming that the generator proper is empty, the top cap, 7, is first removed and the shell or cartridge, 2, is filled with calcium carbid, after which the cap is replaced and secured by means of the fastening device

shown. As a next step the disk valve, 37, is closed, after which the valves, 13 and 21 are opened. The generator is then ready to receive water. At this time the safety valve, 25, is thrown open and water is turned into 70 the reservoir, 15. The water which pours into the reservoir flows downward through the pipe, 14, and the flow is continued until the lower part of the generator is filled, that is, until water begins to waste through the 75 over flow pipe, 22, thereupon the valves 22' and 13 are closed and the supply of water is continued until the reservoir 15, is filled. The hose is then removed from the filling pipe, 23, and the safety valve closed. These 80 things having been done the generator is in condition for use. At this time the water in the lower part of the generator stands within a fraction of an inch from the bottom of the grating, 3. When gas is required 85 the water valve, 13, and also the gas valve, 21, are opened. Immediately upon the opening of the valve, 13, the water falling from the reservoir, 15, will raise the level in the generator, and the carbid on the grating will 90 be partially or completely submerged. The generation of gas will then proceed, the lumps of carbid falling through the grating, into the body of water beneath, as fast as they are sufficiently reduced by decomposition 95 on the grating. The gas thus generated passes through the condenser, to the gas tank, 13, and thence to the burner pipe. The course of the gas is through the annular space between the carbid container and the walls of 100 the generator, and thence through the pipe 17, to the condenser, 18, thence by pipe 20, to the gas tank. The generation of gas continues until the pressure in the generator is sufficient to overcome the head of water in 105 the pipe 14 and the tank 15, whereupon the water will be partially expelled from the generator and the water level therein lowered to a point below the grating. When 110 this occurs the generation of gas will be interrupted. It may not be wholly stopped, for the reason that some of the lumps of carbid which have fallen into the body of water into the lower part of the generator may momentarily continue the generation, 115 but such generation only adds to the expulsion of the water and insures a stoppage of generation before an excessive pressure is attained. It is obvious that the air which is trapped in the upper part of the tank, 15, 120 will be compressed when the water is forced back into the tank from the generator, and that at certain moments the pressure of the air plus the water column will balance the pressure in the generator proper. Obviously 125 this balance is destroyed when gas is withdrawn from the gas tank, and such being the case it is evident that any considerable depletion of pressure will be followed by a rise of water in the generator to again partially sub- 130

merge the calcium carbide which is exposed upon the grating. In this manner the generator responds to every variation of pressure and operates to generate little or much 5 gas according to the varying demands of the system. The operation continues automatically so long as water remains in the reservoir and there is a supply of carbide in the generator. It should be observed that this automatic action is brought about without the 10 use of any mechanical feeding appliances whatsoever, and that the apparatus cannot possibly get out of order, as there are no operating parts to become clogged, or otherwise 15 ineffective.

In this generator we combine the good features and principles of two classes of generators, to-wit, the class known as displacement generators and the class of carbide feeding generators. By so doing we have produced a generator of great simplicity, one 20 which requires absolutely no manual or mechanical control, and one in which the temperature is always low, the gas leaving the generator being cooled and in perfect condition 25 for use.

Having thus described our invention, we claim as new and desire to secure by Letters Patent:

- 30 1. In an acetylene generator suitable for generating acetylene gas under pressure a vertical tube or pipe, in combination with closures for the upper and lower ends thereof, a carbide holder suspended in said tube and grated at its lower end to support the carbide, a gas pipe leading from the upper part of said tube, a separate water tank connected with the lower part of said tube to supply water thereto and means to admit air 35 to said tank when the water is withdrawn, said water tank being sealed to prevent the escape of air while the generator is being operated, whereby said holder being supplied with calcium carbide and water and 40 the gas pipe being open, the generator takes on automatic ebb and flow action and the return of the water into the tank compresses the air contained therein, substantially as described.
- 45 2. In an acetylene generator suitable for generating acetylene gas under pressure, a vertical tube or pipe, in combination with closures for the upper and lower ends thereof, a stationary carbide holder sealed at its top by the upper closure of said tube and open at its lower or generating end, a gas pipe leading from the upper part of said tube, a separate water tank connected with the lower part of said tube to supply water 55 thereto and means to admit air to said tank automatically while the generator is being operated, said water tank being sealed to prevent the escape of air while the generator is being operated, whereby said holder being supplied with calcium carbide and 60
- 65

water and the gas pipe being open, the water in said water tank takes on automatic ebb and flow action occasioned by the variations of pressure in the generator and the return of the water into the tank compresses the 70 air contained therein, substantially as described.

3. In an acetylene generator for generating acetylene gas under pressure, a closed holder for the carbide provided with an outlet for the gas, a water tank sealed to prevent the escape of air and connected with said holder to supply water thereto, and means to admit air to said tank as the water is withdrawn therefrom, whereby a flow of 80 water into said tank under pressure of gas in the holder compresses the air contained in said tank.

4. In an acetylene generator for generating acetylene gas under pressure, a closed holder for the carbide provided with an outlet for the gas, a water tank connected with said holder to supply water thereto, and a valve to admit air to said tank as the water is withdrawn and to prevent the escape of 85 air therefrom whereby the flow of water into said tank under pressure of gas in the holder compresses the air contained in said tank.

5. In an acetylene gas generator, a tube of substantially the same diameter throughout, 95 in combination with a carbide holder having a transverse grating within said tube, substantially midway thereof, a movable closure or cap for the upper end of said tube, a valvular closure for the lower end of said tube, a gas pipe leading from the upper part of said tube, an elevated closed water reservoir, a pipe connecting the same with the lower part of said tube, said reservoir having an air entrance pipe provided with 100 an outwardly closing check valve therefor and an overflow pipe connecting said tube with said air entrance pipe, substantially as described.

6. In an acetylene gas generator, a closed 110 chamber containing a carbide holder having a transverse grating, in combination with a gas pipe leading from the upper part of said chamber, an elevated water reservoir, a water column pipe connecting said reservoir with the lower part of said chamber, a safety valve on said reservoir, an air vent connected with said reservoir and equipped with a one-way check valve, and an overflow connection between said water reservoir 115 and said air vent, substantially as described.

7. In an acetylene gas generator a vertical cylinder, a gas pipe connected to its upper part, a carbide shell arranged in the upper part thereof and sealed except at its lower end, a grating at said lower end, suitable closures for the upper and lower ends of the cylinder, an overflow pipe immediately below said grating and means for maintaining a column of water in communication with 120

the lower end of the cylinder; whereby the accumulation and the depletion of gas pressure within the cylinder will cause the water to alternately rise into contact with and 5 recede from, the carbid.

8. In an acetylene gas generator, a stationary closed chamber, in combination with a transverse grating therein to hold a body of calcium carbid, a gas pipe leading from 10 the upper part of said chamber, a closed water reservoir, a water column pipe depending therefrom and connected with the lower part of said chamber, a filling pipe extending into said reservoir to form an air 15 cushion, and a safety valve on said pipe, substantially as described.

9. A railway car, in combination with a tube or pipe arranged vertically therein with its upper end above the roof of the car, a 20 removable closure for said upper end, a stationary grating or carbid support, provided in said tube, a valve closure for the lower end of said tube and extending beneath the floor of said car, a gas reservoir, a gas duct 25 connecting said tube with said reservoir, and a condenser in said duct and located partly above the roof of the car, and suitable water connections, substantially as and for the purpose described.

10. A railway car, in combination with an acetylene gas generator comprising a tube having its ends extending through the roof and the floor of said car, suitable closures for said tube, a transverse grating in said 35 tube to support a body of carbid in the upper part thereof, a closed water reservoir in the upper part of said car, a filling pipe extending into said reservoir to form an air cushion, an external safety valve for said reservoir, a valved water pipe connecting said reservoir with the lower part of said tube, an overflow pipe provided with a valve arranged above the inlet of said tube and a gas 40 pipe leading from the upper part of said tube, substantially as described.

11. A railway car, in combination with an acetylene gas generator comprising a tubular body having closed ends on the exterior of the car, a sealed carbid container in the upper 50 part of said body and open only at its lower end, a water reservoir arranged in the upper part of said car and connected with the lower part of said tubular body, an external safety valve for said water reservoir, a suitable air inlet check valve for said reservoir, and a gas duct extending from the upper part of said body through the roof of the car into the air, and thence downward 55 through the floor of the car, substantially as described.

12. In an acetylene gas generator, a vertical tube or pipe, in combination with closures for the upper and lower ends of said tube, a pocket in the closure for the lower 60 end, a rotatable disk in said pocket, a dis-

charge opening in said closure member, and a port in said disk, means for turning said disk to open or close said discharge opening, a carbid holder suspended in said tube, and suitable gas and water connections, substantially as described. 70

13. In an acetylene gas generator, a vertical tube or pipe, in combination with upper and lower closures for the end of said tube, said lower closure being hinged upon 75 the bottom of said tube and provided with a discharge opening, and a valve adapted to open and close said discharge opening means to operate said valve comprising a shaft projecting through said closure and provided 80 with a handle, a carbid holder suspended in said tube, and suitable gas and water connections, substantially as described.

14. A railway coach lighting system comprising a coach, in combination with a vertical tube arranged in the side of the coach, said coach having openings in its floor and roof through which the ends of said tube extend, a removable cap or closure upon the upper end of said tube, a base plate wherein 90 the lower end of said tube is secured, a removable closure on the under side of said base plate, a discharge spout provided therein, a valve arranged in the closure upon said plate and normally closing said spout, means 95 beneath the coach for operating said valve, a gas outlet pipe connected with the upper end of said tube at a point within the coach, a valved overflow pipe connected with the lower part of said tube and extending 100 through the floor of the coach, a water tank arranged in the upper part of the coach, a pipe leading therefrom, and connected with said tube at a point beneath said overflow pipe, and a carbid grating arranged in said 105 tube at a point slightly above said overflow pipe, substantially as described.

15. A railway coach lighting system comprising a coach, in combination with a vertical tube arranged in the side of the coach, 110 said coach having openings in its floor and roof through which the ends of said tube extend, a removable cap or closure upon the upper end of said tube, a base plate wherein the lower end of said tube is secured, a removable closure on the under side of said base plate, a discharge spout provided therein, a valve arranged in the closure upon said plate and normally closing said spout, means 115 beneath the coach for operating said valve, a gas outlet pipe connected with the upper end of said tube at a point within the coach, a valved overflow pipe connected with the lower part of said tube and extending 120 through the floor of the coach, a water tank arranged in the upper part of the coach, a pipe leading therefrom, and a carbid grating 125 arranged in said tube at a point slightly above said overflow pipe, substantially as described. 130

16. A railway coach lighting system comprising a coach in combination with a vertical tube arranged in the side of the coach, said coach having openings in its floor and roof through which the ends of said tube extend, a removable cap or closure upon the upper end of said tube, a base plate wherein the lower end of said tube is secured, a removable closure on the under side of said base plate, a discharge spout provided therein, a valve arranged in the closure upon said plate and normally closing said spout, means beneath the coach for operating said valve, a gas outlet pipe connected with the upper end of said tube at a point within the coach, a valved overflow pipe connected with the lower part of said tube and extending through the floor of the coach, a water tank arranged in the upper part of the coach, a pipe leading therefrom, and connected with the said tube at a point beneath said overflow pipe, and a tubular carbide holder of less diameter than said tube and suspended therein and a grating arranged in the bottom of said carbide holder, substantially as described.

17. A railway coach lighting system comprising a coach in combination with a vertical tube arranged in the side of the coach, said coach having openings in its floor and roof through which the ends of said tube extend, a removable cap or closure upon the upper end of said tube, a base plate wherein the lower end of said tube is secured, a removable closure on the under side of said base plate, a discharge spout provided therein, a valve arranged in the closure upon said plate and normally closing said spout, means beneath the coach for operating said valve, a gas outlet pipe connected with the upper end of said tube at a point within the coach, a valved overflow pipe connected with the lower part of said tube and extending through the floor of the coach, a water tank arranged in the upper part of the coach, a pipe leading therefrom, and connected with said tube at a point beneath said overflow pipe, and a carbide grating arranged in said tube at a point slightly above said overflow pipe, substantially as described.

18. A railway coach lighting system comprising a coach, in combination with a vertical tube arranged in the side of the coach, the ends of said tube extending through the floor and roof thereof, a removable cap or closure upon the upper end of said tube, a base plate wherein the lower end of said tube is secured, a discharge spout provided therein, a valve arranged in the closure upon said plate and normally closing said spout, a gas outlet pipe connected with the upper end of said tube at a point within the coach, a valved overflow pipe connected with the lower part of said tube and extending through the floor of the coach, a water tank

arranged in the upper part of the coach, a pipe leading therefrom and connected with said tube, a valved air inlet pipe connected with said tank and opening through the bottom of said coach, and a carbide grating arranged in said tube, substantially as described. 70

19. A railway coach lighting system comprising a coach, in combination with a vertical tube arranged in the side of the coach, said coach having openings in its floor and roof through which the ends of said tube extend, a removable cap or closure upon the upper end of said tube, a base plate wherein the lower end of said tube is secured, a removable closure on the under side of said base plate, a discharge spout provided therein, a valve arranged in the closure upon said plate and normally closing said spout, means beneath the coach for operating said valve, a gas outlet pipe connected with the upper end of said tube at a point within the tube, a gas reservoir under said coach, a reducing valve and burner pipe, a valved overflow pipe connected with the lower part of said tube and extending through the floor of the coach, a water tank arranged in the upper part of the coach, a pipe leading therefrom, and connected with said tube at a point beneath said overflow pipe, and a carbide grating arranged in said tube at a point slightly above said overflow pipe, substantially as described. 80

20. A railway coach lighting system comprising a coach, in combination with a vertical tube arranged in the side of the coach, said coach having openings in its floor and roof through which the ends of the tube extend, a removable cap or closure upon the upper end of said tube, a closure for the lower end of said tube provided with a valved discharge pipe, a valved overflow pipe connected with the lower part of said tube and extending through the floor of the coach, a water tank arranged in the upper part of the coach, a pipe leading therefrom and connected with said tube at a point beneath said overflow pipe, a carbide grating arranged in said tube, a gas reservoir beneath said coach, a gas outlet pipe connecting said tube with said reservoir, a condenser interposed in said pipe and extending through the roof of said coach, a reducing valve and a burner pipe, substantially as described. 100 105 110 115

In testimony whereof, we have hereunto set our hands, this 17th day of March, 1906, at St. Paul, Ramsey county, Minnesota, in the presence of two subscribing witnesses.
